FOOT MEASURING STICK

Harry N. Wheeler, Birmingham, Ala., assignor to
Wheeler-Morse Company, Birmingham, Ala., a
corporation of Delaware

Application March 9, 1933, Serial No. 660,119

9 Claims. (Cl. 33—3)

This invention relates to improvements in foot measuring sticks and has for its object to improve upon the stick described and claimed in patent to Wheeler No. 1,507,539, September 2, 5 1924.

Said patent discloses generally a stick comprising a flat plate with an upturned heel piece at one end and carrying length and width scales, in combination with a detachable slide constructed to move both crosswise and longitudinally on the base, the slide having an upstanding lug associated with an index or pointer in a slot. The width scale on the base comprises diagonal parallel lines marked in width sizes, operating in conjunction with a width scale marked on the rear of the slide. Such a device has worked satisfactorily for both rights and lefts in adults' and children's sizes, but owing to the detachability of the slide and the arrangement of scales, some inconveniences have arisen in both manipulation 15 and obtaining quick and accurate readings which this invention overcomes.

According to this invention, I mount the slide permanently on the base so that it can move crosswise in obtaining overall lengths and widths, and move longitudinally on either side to obtain arch lengths, being movable from one side to the other without requiring detachment. In the preferred form herein shown, the slide is mounted to 20 run in a trackway on the underside of the base without being interfered with by the floor on which the stick rests when in use, and can readily be shifted from side position measuring the arch length to crosswise position for obtaining overall 25 length and width.

In conjunction with such improved slide, a system of length and width scales is provided in association with an indicator and slots in the slide whereby the operator more quickly obtains 30 direct readings on parallel scales. The novel scale arrangement I have devised retains the longitudinal central scale and edge scales of said patent, but interposes on one side, an adult's width scale, and on the other side, a child's width scale, and on the slide provides corresponding slots 35 graduated in length sizes so that adult's width is obtained by direct and positive reading through one slot in the slide, and children's widths likewise through another. This system is found to be quicker and more accurate than the width reading system including diagonal width 40 lines disclosed in said patent. Also, it is possible in this device to carry the heel to ball scale on either side of the base from adults right down to 45 children's sizes, which is a decided advantage and

not, so far as I know, embodied in any previous device.

In the accompanying drawing,

Fig. 1 is a plan view;

Fig. 2 is a section on the line 2—2 of Fig. 1; and 5

Fig. 3 is a section on the line 3—3 of Fig. 1.

1 represents the base which may conveniently be of die cast aluminum having a heel piece 2 at one end, curved to receive the heel in length measuring, and the small toe in width measuring. 10 On the underside of the base is a trackway 3 extending along each side and around the end, and within the trackway are ribs or extensions 4 which form a base. Mounted to slide in the trackway from one side around to the other and crosswise is a slide 6 having inturned end 7 to underlie the trackway and carrying on extensions 8, screws or pins 9 to hold the slide in the track. Preferably as shown in dotted lines in Fig. 1, the trackway is curved around the outer end on a 15 radius such, in connection with the location of pins 9, as to enable the slide to move from one edge to the other as in measuring one foot and then the other, or to slide crosswise in the position shown in Fig. 1. 25

The slide is provided with a curved lug 10 to contact with the end of the great toe in obtaining overall length, and with the great toe ball joint when sliding on the side of the base to obtain arch length, which is the distance from the heel to the 30 said joint. By the structure indicated and shown, it is seen that the slide is held out of contact with the floor and can be easily slid around and up and down as desired.

The slide in the rear of lug 10 is provided with 35 a central indicating slot 11 and pointer 12. On one side is a width reading slot 13 as for adults, and on the other side, a width reading slot 14 as for children. Each of these slots is graduated 40 along one edge, as at 16, 17 respectively with corresponding length graduations.

The base is provided with a central length scale 18 which starts at children's sizes and then continues into adult sizes as shown and all cooperate with pointer 12. On the right, as seen in 45 Fig. 1 is an outside scale 19 for giving arch measurements in terms of size for the right foot, and on the other side, is a similar scale 20 for the left foot, each of these scales likewise running from children's sizes into adult sizes. 50

Between the central scale and the edge scale, as on the right side, is a width scale 22 for adults, and on the left side is a similar scale 23 for children's widths, the scale 22 cooperating with reading slot 13 and scale 16 on the side, and the 55

scale 23 cooperating with reading slot 14 and scale 17 on the slide.

Measurements, preferably for both feet, because feet are often of different size, are made as follows:

1. *Arch length.*—Place the foot with the heel firmly against the heel piece 2. Move the slide on the appropriate side of the base to rest the lug 10 firmly against the center of the great toe joint, 10 and read the size on side scale 19 or 20 by pointer 12.

2. *Foot length.*—Without moving the foot, bring slide over the end and crosswise with lug 10 against the end of the longest toe, then press the 15 toes flat with the hand, and read the size at pointer 12 on the scale 18. As these two length indications seldom agree, the longest length indication should be taken.

3. *Foot width.*—Place the outside of the foot 20 firmly against heel piece 2 and move the slide lug 10 against the center of the large toe joint. Then press the slide gently against the foot and read the width required for an adult opposite the size selected on scale 22 and graduations 16. For 25 children's width, use the scale 23 seen through slot 14 and graduations 17.

This measuring stick combines in one convenient and practical device, means for measuring both adults' and children's feet for heel to ball length, heel to toe length, and width, and either right or left foot. By attaching the slide to the base so that it can be moved around without difficulty while in use, I add to the convenience of the above features, while the arrangement of 35 pointer, slots and scales makes possible a direct and positive reading of the width required for the previously determined length and, so far as I know, for the first time makes it possible to run length scales for heel to ball measure from adults' 40 right down to children's sizes.

The invention claimed is:

1. A foot measuring stick comprising a stick member having a heel piece at one end, a trackway along the sides and around the opposite end, 45 scales adjacent the edges and centrally of the stick, a slide mounted in said trackway and movable longitudinally and crosswise of the stick, and indicating means carried by the slide and cooperating with said scales.

50 2. A foot measuring stick comprising a stick member having a heel piece at one end, a trackway on the underside along the sides and around the opposite end, scales adjacent the edges and centrally of the stick, a slide mounted in said trackway and movable longitudinally and crosswise of the stick, and indicating means carried by the slide and cooperating with said scales.

3. A foot measuring stick comprising a stick member having a heel piece at one end, a trackway on the underside elevated above the bottom along the sides and around the opposite end, scales adjacent the edges and centrally of the stick, a slide mounted in said trackway and movable longitudinally and crosswise of the stick, 60 and indicating means carried by the slide and cooperating with said scales.

4. A foot measuring stick comprising a stick member having a heel piece at one end, a trackway along the sides and around the opposite 65 end, scales adjacent the edges and centrally of

the stick, a slotted slide mounted in said trackway and movable longitudinally and crosswise of the stick, and indicating means carried by the slide at one side of said slot and cooperating with said scales.

5. A foot measuring stick comprising a stick member having a heel piece at one end, a length scale centrally of the stick, a width scale intermediate the central scale and one edge, and a slide movable on the stick, said slide having a 10 central slot and pointer for obtaining lengths from said length scale, and a slot with graduations of width size variation designated by corresponding length size indicia for obtaining widths from said width scale. 15

6. A foot measuring stick comprising a stick member having a heel piece at one end, a length scale centrally of the stick, an adult's width scale on one side of said central scale, a child's width scale on the other side of said central scale, and 20 a slide movable on the stick, said slide having a central slot and pointer for obtaining lengths from said length scale, and width indicating slots with graduations of width size variation designated by corresponding length size indicia on 25 opposite sides thereof cooperating with said width scales.

7. A foot measuring stick comprising a stick member having a heel piece at one end, a foot length scale centrally of the stick, an adult's width 30 scale on one side of said central scale, a child's width scale on the other side of said central scale, arch length scales adjacent the longitudinal edges of the stick and a slide movable longitudinally and crosswise of the stick, said slide having a 35 central slot and pointer cooperating with said foot and arch length scales for obtaining foot and arch lengths, and width indicating slots on opposite sides thereof cooperating with said width scales, said width slots having graduations in 40 foot length units to enable the required width to be determined relatively to the ascertained length.

8. A foot measuring stick comprising a stick member having a heel piece at one end, foot and arch length scales longitudinally of the stick running continuously through children's lengths and through adults' lengths, a longitudinal child's width scale adjacent the heel piece, a separate longitudinal adult's width scale also adjacent the heel piece, and a slide movable longitudinally and 45 crosswise of the stick having a slot and pointer cooperating with said foot and arch length scales, and slotted and graduated in foot length units to cooperate with said adult's and child's width scales. 50

9. A foot measuring stick comprising a stick member having a heel piece at one end, a length scale longitudinally of the stick running continuously from children's lengths through adults' 60 lengths, a longitudinal child's width scale adjacent the heel piece, a separate longitudinal adult's width scale also adjacent the heel piece, and a slide movable longitudinally and crosswise of the stick having length indicating means cooperating with said length scale when moving longitudinally 65 on the stick and width indicating means cooperating with said width indicating scales when moving in crosswise relation on said stick.
